(57) **CLAIM**

The ornamental design for a can rack with mesh walls, as shown and described.

DESCRIPTION

FIG. 1 is a perspective view of a can rack with mesh walls in accordance with my design;

FIG. 2 is a top plan view of the can rack with mesh walls;

FIG. 3 is a front elevational view thereof;

FIG. 4 is a left side elevational view thereof, with the right side elevational view being a mirror image thereof;

FIG. 5 is a rear elevational thereof; and,

FIG. 6 is a bottom plan view thereof.
